INVENTOR

Marcus A. Adler

BY *John*

ATTORNEY S.

UNITED STATES PATENT OFFICE.

MARCUS A. ADLER, OF NEW YORK, N. Y., ASSIGNOR TO CHARLES S. ADLER, OF SAME PLACE.

CLOTH-CUTTING APPARATUS.

SPECIFICATION forming part of Letters Patent No. 659,119, dated October 2, 1900.

Application filed January 24, 1900. Serial No. 2,649. (No model.)

To all whom it may concern:

Be it known that I, MARCUS A. ADLER, a citizen of the United States, residing at Manhattan borough, New York city, in the county 5 and State of New York, have invented new and useful Improvements in Tailors' Tables, of which the following is a specification.

This invention relates to certain novel features of construction by which the cutting of 10 garments or material can be readily and expeditiously carried on, as set forth in the following specification and claims and illustrated in the annexed drawings, in which—

Figure 1 is a plan view of the table. Fig. 15 2 is an inverted plan view of Fig. 1. Fig. 3 is a section along A A, Fig. 1. Fig. 4 is a side elevation of a rotary supporting portion. Fig. 5 is a section along B B, Fig. 4. Fig. 6 shows a lock. Fig. 7 is a section along 20 C C, Fig. 6. Fig. 8 is a section along D D, Fig. 6. Fig. 9 is a plan of the rotary ring to which the rollers are attached. Fig. 10 is a plan of the non-rotary base or ring on which the rollers run.

25 The table-top *a* has supporting-legs *b* and *c* and is slotted. The slots *d* are shown running longitudinally and the slots *d'* run transversely.

The rotary supporting portion comprises 30 strips *e*, spaced, as seen at *f*, to correspond with the slots *d d'* in the table-top. The risers *g* support strips *e*. The risers being independent or spaced from one another severally support the strips so that a knife can be run 35 from a slot *d* or *d'* into and out of a slot *f*. The rotary or swivel base *h* for the risers enables the top to be rotated so that slots *f* can be set in line with or at an angle to slots *d* or *d'*, as required by the operator. The risers are supported on a rotary or swivel base *h*, which 40 can rotate about the pivot or point *i*. The supporting-rollers *k* for the base enable the latter to run easily or without friction.

To lock or hold the rotary base, a lock or 45 pin *q*, Fig. 3, can engage a suitable eye or perforation in the base. A suitable number of perforations are provided to lock the rotary part with slots *f* straight or on the bias relatively to the fixed slots *d*. The lock *q* is 50 carried by a spring *r*, tending to snap or hold

the lock in action or engaging position. A slide or release *s* has a high or wedge part, which when the slide is moved one way acts against spring *r* to free or withdraw lock *q*. A lever *t*, with second slide *s'*, can be made to 55 return the first slide *s* to allow lock *q* to move back into action. The slides *s s'* when located at the lower part of the device to be within reach of the foot of the operator allow the latter's hands to be kept free for cutting 60 or for working at the top of the table. The rollers *k* are carried or journaled on a rotary ring *k'* and run on a fixed or non-rotary base or ring *k''*. The screws *h''* enable the fixed base *k''* to be leveled or adjusted so that the 65 rotary part *e* will be on a level with top *a*. The transverse pieces *g'*, Fig. 4, tend to steady the risers *g* of a strip *e*. The base *h* has recesses *h'*, into which can be placed a foot or toe part of a foot to rotate the strips *e*. 70

The table and all parts being made throughout of metal, such table will not wear nor warp and shrinkage is avoided, so that cloth or material can be supported flush or as required for cutting, so that even if a number 75 of layers of material are placed on the table at once the lower layer of goods, with the others, is evenly or properly supported and cannot slip or work out of place or between parts *e* and *a*. At the ends of slots *d d'* are 80 soft or yielding abutments *d''*—such as fillers of rubber, cork, or the like—to guard the edge of the knife or cutting-tool.

What I claim as new, and desire to secure by Letters Patent, is— 85

1. A slotted table-top having supporting-legs and provided with a rotary supporting portion comprising strips spaced to correspond with the slots in the table-top, risers for severally supporting the strips, and a rotary or swivel base for the risers, all of said parts being made throughout of metal and said table-top having soft or yielding abutments or fillers at the ends of the slots substantially as described. 90

2. A table-top having series of longitudinal and transverse slots and supporting-legs and provided with a rotary supporting portion comprising strips spaced to correspond with the slots in the table-top, risers for severally 95 100

supporting the strips, and a rotary or swivel base for the risers, all of said parts being made throughout of metal and said table-top having soft or yielding abutments or fillers at the ends of the longitudinal and transverse slots substantially as described.

In testimony whereof I have hereunto set

my hand in the presence of two subscribing witnesses.

MARCUS A. ADLER.
